[57] CLAIM

The ornamental design for a compact case, as shown and described.

DESCRIPTION

FIG. 1 is a front perspective view of the compact case.

FIG. 2 is a top plan view of the compact case.

FIG. 3 is a right side elevational view of the compact case.

FIG. 4 is a left side elevational view of the compact case; and,

FIG. 5 is a bottom plan view of the compact case.

1 Claim, 2 Drawing Sheets

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.
